(57) **CLAIM**

The ornamental design for a two piece rifle receiver and tail, as shown and described.

DESCRIPTION

FIG. 1 is a left side perspective view of the two piece rifle receiver and tail.

FIG. 2 is a right side perspective view of the two piece rifle receiver and tail.

FIG. 3 is a front end view of the two piece rifle receiver and tail.

FIG. 4 is a back end view of the two piece rifle receiver and tail.

FIG. 5 is a left side view of the two piece rifle receiver and tail.

FIG. 6 is a right side view of the two piece rifle receiver and tail.

FIG. 7 is a top view of the two piece rifle receiver and tail; and, FIG. 8 is a bottom view of the two piece rifle receiver and tail. The broken line showing of aspects of the two piece rifle receiver and tail forms no part of the claimed design.
